ROCKING HORSE

William C. Lutz, Union, N. J.

Application April 15, 1944, Serial No. 531,230

6 Claims. (Cl. 272—52)

The invention here disclosed relates to children's toys in the nature of rocking or hobby horses.

Special objects of the invention are to provide a toy of the character indicated, which while of simple construction and of artistic design, such as would appeal to a child, will have capability of adjustment to suit the size or age of the child and in which the means of such adjustment will be practically concealed and unseen, so as not to impart any mechanical sense or otherwise detract from the more or less natural appearance of the horse figure.

Further special and related objects are to provide a hobby horse construction of such a nature that it may be quickly converted from one size or height to suit the growth of a child who may have become attached to the toy and thus to avoid the frequent occurrence of the child "out-growing" and losing the benefit of what may have become a desired "companion."

Other objects of the invention are to provide a toy such as outlined, which will be perfectly safe for a child to play with, free of projections or extra parts which might cause injury and which with all its advantages, will be relatively inexpensive and made up of readily available materials.

Other desirable objects and the novel features by which the purposes of the invention are attained will appear or are set forth in the following specification.

The drawing accompanying and forming part of the specification illustrates a practical and at present preferred embodiment of the invention, but structure may be modified and changed all within the true intent and broad scope of the invention as hereinafter defined and claimed.

Fig. 1 in the drawing is a side elevation of the toy with parts broken away and appearing in section.

Fig. 2 is a vertical sectional view as on line 2—2 of Fig. 3, showing the parts assembled to provide a lower figure.

Fig. 3 is a top plan view of the horse.

Fig. 4 is an enlarged broken sectional detail as on substantially the plane of line 4—4 of Fig. 1.

The figure portion of the invention is shown as made up of a body part 1, forelegs 8, and hindlegs 9, and these several parts as cut from wood, in shapes to create the general effect of a running horse.

The legs are connected with the body portion by concealed joints in the form of dowels or pins extending from the legs at opposite sides, through the intermediate body portion. The location of these pins or dowels is important in that it enables the setting of the legs in different natural appearing outstretched relations and the securing of them firmly in such positions.

The forelegs are secured to the body at the top by a dowel or pin 10, located approximately on the axis of what would be considered the shoulder joint of the animal figure.

5 Similarly, the hindlegs are attached to the body by a dowel or pin 11, disposed substantially on what might be considered the hip joint of the figure.

10 Each pair of legs is retained in a desired outstretched angular relation by a second dowel or pin, extending through a selected one of a number of openings in the body.

15 Thus the front legs are shown as having a second dowel 12, extending through one opening 13, as in Fig. 1, or through another opening 14, Fig. 2, which are at the same radial distance from the passage 15, for the fixed-center dowel 10.

20 Similarly, the hindlegs are held by a dowel 16, extending through one passage 17, Fig. 1, or through a second angularly offset passage 18, Fig. 2, at equal radial distances from the passage 19, for the hip axis dowel 11.

25 The dowels and the parts which they locate and connect may be secured in various ways. In the present embodiment, both the dowels for one pair of legs are fixedly secured in one of the legs of such pair, as indicated at the left in Fig. 4, and extend through the passages in the body into seats 20, 21, provided to receive them in the other leg. The parts may then be fastened in this assembled relation by a screw or screws such as indicated at 22, positioned to engage the end or ends of the dowel or dowels entered in such socket or sockets.

30 The lower ends of the legs are shown connected and supported by cross rods 23, 24, and the ends of these rods as seated in sockets 25, 26, Fig. 1, or 27, 28, Fig. 2, in the inner faces of the rockers 29.

35 The legs of each pair may be releasably secured in properly spaced substantially parallel relation on the supporting rods 23 and 24 as by screws such as indicated at 30, Fig. 2.

40 45 The rockers are separably secured together, in the present disclosure by a board or foot rest 31, detachably fastened to cleats 32 at one or both ends by screws 33.

50 The body portion of the device may carry a suitable saddle or seat such as indicated at 34, bridle and other accoutrements or decorations.

55 In both the high and the low positions, Figs. 1 and 2, the parts are well braced and firmly secured. To change from one condition to the other, it is only necessary to separate the rockers, as by removing the screws 33, at one end of the foot rest and to then loosen and remove one leg of each pair. This can be accomplished by releasing screws 22 and 30, of one front leg and one rear leg. When this is done, the legs of

each pair can be separated, as in Fig. 4, and the legs carrying the dowels 10, 12, and 14, 16, be separated from the body and then be replaced with the axis dowels 10 and 11 in passages 15 and 19, but the fulcrum dowels 12 and 16, in the other of the two sets of openings 13, 16 and 14, 18. In the change from the Fig. 1 to the Fig. 2 position the lower, fulcrum dowels 12, 16, would be extended through openings 14, 18, respectively, in the body and the other set of legs engaged over the projecting ends of the dowels at that side of the body. In replacing the rockers over the ends of the cross rods 23, 24, the latter will then be engaged in the other of the two sets of openings 25, 26 and 27, 28, in this case the openings 27, 28.

The change can thus be quickly and easily made by one having no special experience in the handling of tools.

The figure is attractive in both positions. By provision of additional fulcrum openings such as 13, 14 and 16, 18, other postures of the animal figure could be provided for, but for general purposes, the two positions illustrated are sufficient for all practical purposes. The legs, engaged as they are flat against the opposite sides of the body member firmly brace and in turn are braced by the latter. The flat form of the several parts, particularly the body, legs, rockers and foot rest and their ready detachability, are of particular importance for packing and shipping purposes, enabling the article to be closely packed in small space. Making the parts of flat board also enables the device to be inexpensively but attractively finished by simple painting methods. The dowels, screws and other positioning and securing parts are concealed and out of the way. While the device has been described as a horse, it will be realized that this term has been used in a descriptive sense as the invention could be made up to resemble other forms of animals or objects. Similarly as to other terms employed for descriptive purposes, such as "dowel," which has been used to describe the connecting means extending through the body into the leg members at opposite sides of the same.

What is claimed is:

1. A rocking horse comprising rockers, means for separably securing the same in spaced relation, cross rods arranged to be held between said rockers at different distances apart, leg members on said cross rods, a body member supposable by said leg members in different angular positions of the latter, said body member having passages therethrough for locating the upper ends of the leg members and other passages grouped in the same radial distances about said upper end passages, the leg members having passages at the upper end of the same for registry with said end locating passages first mentioned and other passages for registry with selected ones of the other body passages and dowels extending through the body passages into engagement in the leg member passages.

2. A rocking horse comprising a body member having passages therethrough, substantially at the shoulder and hip joint positions of the body member and other passages grouped in angular relation and at the same radial distance from said joint located passages, pins extending through said joint located passages and other pins removably and selectively engageable in the other angularly related passages and leg mem-

bers removably engageable over the opposite ends of said pins, at opposite sides of said body member.

3. A rocking horse comprising a body member having passages therethrough substantially at the shoulder and hip joint positions of the body member and other passages grouped in angular relation and at the same radial distance from said joint located passages, pins extending through said joint located passages and other pins removably and selectively engageable in the other angularly related passages, leg members removably engageable over the opposite ends of said pins, at opposite sides of said body member, cross rods connecting the lower ends of said leg members and rockers having differently spaced sockets positioned to receive the ends of said cross rods in the different positions of said leg members.

4. A rocking horse, comprising a body member and leg members at the opposite sides of said body member, dowels pinning said leg members against the opposite sides of said body member, there being two dowels to each pair of leg members and located one at the upper end of each pair of leg members and the other at a distance below the upper end, the body member having passages extending entirely therethrough and the leg members having passages entering the inner faces of the same for reception of said dowels and there being a plurality of passages for the lower dowels selectively engageable to effect the setting of the leg members at different angles on the body member.

5. A rocking horse, comprising a body member and leg members at the opposite sides of said body member, dowels pinning said leg members against the opposite sides of said body member, there being two dowels to each pair of leg members and located one at the upper end of each pair of leg members and the other at a distance below the upper end, the body member having passages extending entirely therethrough and the leg members having passages entering the inner faces of the same for reception of said dowels and there being a plurality of passages for the lower dowels selectively engageable to effect the setting of the leg members at different angles on the body member, said plural openings being in the form of passages extending entirely through the body member in different angular positions but at the same radial distances from the passages for the upper dowels.

6. A rocking horse, comprising a body member and leg members at the opposite sides of said body member, dowels pinning said leg members against the opposite sides of said body member, there being two dowels to each pair of leg members and located one at the upper end of each pair of leg members and the other at a distance below the upper end, the body member having passages extending entirely therethrough and the leg members having passages entering the inner faces of the same for reception of said dowels and there being a plurality of passages for the lower dowels selectively engageable to effect the setting of the leg members at different angles on the body member and readily releasable means for detachably securing the leg members in the different angular positions described.

WILLIAM C. LUTZ.
